UNITED STATES PATENT OFFICE

ERNST H. LOHRMANN, OF PROVIDENCE, RHODE ISLAND, ASSIGNOR TO THE WILLIAMS BROTHERS MANUFACTURING COMPANY, OF GLASTONBURY, CONNECTICUT, A CORPORATION OF CONNECTICUT.

DESIGN FOR A SPOON, FORK, OR SIMILAR ARTICLE.

43,197.

Specification for Design.

Patented Oct. 29, 1912.

Application filed June 25, 1912. Serial No. 705,879. Term of patent 7 years.

To all whom it may concern:

Be it known that I, ERNST H. LOHRMANN, a citizen of the United States, and a resident of Providence, in the county of Providence and State of Rhode Island, have invented a new, original, and ornamental Design for Spoons, Forks, or Similar Articles, of which the following is a specification, reference being had to the accompanying drawings, forming part thereof.

Figure 1 is a view of the obverse side of a

spoon embodying my invention. Fig. 2 is a view of the reverse side thereof. Fig. 3 is a detail perspective view of the end of the spoon handle.

I claim—

The ornamental design for a spoon, fork or similar article, as shown.

ERNST H. LOHRMANN.
